No. 37,181.

Patented October 11, 1904.

UNITED STATES PATENT OFFICE.

FRANK HUNDORF, OF COVINGTON, KENTUCKY.

DESIGN FOR A FOUNTAIN-AQUARIUM.

SPECIFICATION forming part of Design No. 37,181, dated October 11, 1904.

Application filed August 29, 1904. Serial No. 222,674. Term of patent 7 years.

To all whom it may concern:

Be it known that I, FRANK HUNDORF, a citizen of the United States, residing at Covington, in the county of Kenton and State of Kentucky, have invented a new, original, and ornamental Design for Fountain-Aquariums, reference being had to the accompanying drawing, which shows my design in perspective view.

I claim—

The ornamental design for a fountain-aquarium, substantially as shown.

FRANK HUNDORF.

Witnesses:

C. SPENGEL,
ARTHUR KLINE.
